APPARATUS FOR SEPARATING MATERIALS OF VARYING DEGREES OF CONDUCTIVITY

Application filed July 12, 1928. Serial No. 292,111.

This invention relates to an apparatus for separating materials of varying degrees of conductivity in accordance with the process set forth in my co-pending application, Serial No. 292,110, filed on the 12th day of July, 1928.

The object of the invention is to provide a separating apparatus comprising a pair of spaced electrodes, over which materials having varying degrees of conductivity or, and, fusibility are fed; certain of the material completing an electric circuit, by its presence between said electrodes, the completion of said circuit causing such flow of current through said material as to bring about the fusing of the same. More specifically, the invention resides in utilizing two electrodes, one of which travels without changing its distance from the other electrode, the fused material adhering to said travelling electrode and being carried away from the gap by the movement of said electrode, so that the process is rendered a continuous one.

It is a further object of the invention to provide apparatus for carrying out the process of separating, as above set forth, in conjunction with means for automatically interrupting the current flow as the fused material moves away from the gap at which it was fused, to thereby prevent the formation of an electric arc, as said fused material moves away from the fixed electrode.

Further objects and advantages of the invention will be set forth in the detailed description which follows.

In the accompanying drawing:

Fig. 1 is a perspective view of the separating apparatus;

Fig. 2 is a perspective view of a current regulating and controlling device used in conjunction with Fig. 1.

Fig. 3 is a detail view, upon a larger scale, of a part of the mechanism of Fig. 2, and

Fig. 4 is a transverse sectional view through the rollers, and associated parts, of Fig. 1.

Like numerals designate corresponding parts throughout the several figures of the drawing.

Rollers A are disposed upon opposite sides of, and in close proximity to, a stationary

separating plate B, of inverted V-shape. These rollers and the separating plate are made of any suitable metal to constitute them conductors of electricity. Troughs C are provided with scraping edges c, which lie in contact with the outer sides of the rollers A. The rollers A are journaled in bearings D, said bearings being supported upon the inclined upper side of a frame E. A transverse shaft J, driven by belt M, is mounted in bearings K, and carries bevel pinions H, which mesh with bevel pinions L, upon the ends of the shafts C, of the rollers A. This mechanism serves to rotate the rollers in the directions indicated by the arrows a. The stationary separating plate B rests upon plates of insulating material Z. The troughs C are carried by rods f, which are adjustable toward and from the rollers, as shown at F. The current controlling and regulating mechanism comprises a solenoid magnet T, the ends of the winding of which are indicated at X and W. This winding is wound about the hollow tube T, in which the core S, of the solenoid, moves. A wire V is connected to this core and extends to a source of current supply. The terminal X of the solenoid magnet also extends to the source of supply of the current. The core of the solenoid magnet carries a carbon contact point R, which co-acts with contact point Q, on support O. This support is adjustable upon a panel H, as indicated at P. A wire, or conductor Y, leads from the contact point Q to the fixed plate B. Thus, the circuit is as follows:

From the source of supply through wire V to core S; thence through contact points R and Q, when these are in engagement with each other, through wire Y to separating plate B. When the gap between a longitudinal edge of B, and either of the rollers A, is bridged by a particle or particles of metal, the circuit will be completed through the said roller, wire W, the solenoid winding and wire X, back to the source of current supply. The completion of this circuit through the particles of metal to be separated brings about such fusing of the metal as will cause it to adhere to the roller A. The metal then travels around with the roller A, until it is

scraped off by the corresponding scraper *c* and deposited in the corresponding long trough *C*. It will be understood that the strength of the current employed will be such as to fuse the particular metal that it is desired to separate, and the current controlling and regulating device of Fig. 2 is designed to render it possible to vary the strength of the current, as may be needful.

10 As has been stated, the rollers *A* are disposed upon an angle. This, coupled with the fact that they continuously rotate in the direction of the arrows *a*, brings about a constant lifting and rotating of the ore which is fed upon the rollers at the upper end thereof; the gangue being discharged from the lower ends of said rollers. If, for example, gold bearing placer gravel, or other gravel bearing gold particles, is deposited upon the 15 upper ends of the rollers and fed downwardly thereover, the gravel being a non-conductor of electricity, or of high resistance, passes over the rollers without being affected. The constant lifting and agitation of the gravel, 20 as it feeds slowly downward over the rollers, causes the relatively heavy metal content, or the metal bearing content thereof, to seek the lowest point of the mass, which is the point where the longitudinal edges of the separating plate *B* lie closest to the rollers *A*. When 25 either of the gaps *x* is bridged by a conductive particle of metal, a fusing of the metal takes place, as above described.

It will be apparent that since the winding 30 of the solenoid is in series with the fusing circuit, the solenoid will be energized when the circuit is completed. The energizing of the solenoid causes the contact *R* to be lifted, thus breaking the fusing circuit. Consequently, when the fused particle is carried 35 away from the gap *x*, the arc that would otherwise occur is prevented. As soon as the fused particle moves away from the gap, the solenoid is de-energized and the core *R* drops, so that when additional metallic particles 40 come into the gaps *x*, they will again complete a circuit to bring about the fusing thereof upon the carrier electrodes, or rollers *A*.

45 Since the contact point *Q* is adjustable, with respect to contact point *R*, it follows that the amperage of the current may be varied in accordance with the different sizes, conditions and natures of the metallic particles to be extracted. It is clear that many 50 mechanical appliances can be devised, by those skilled in the art, that will do the work proposed to be done by this apparatus. Consequently, it is to be understood that the invention is not limited to the precise construction 55 shown in the drawing, but that it includes, within its purview, all reasonable modifications thereof, coming within either the terms or the spirit of the appended claims.

60 Furthermore, while the bulk of the valuable

content of the ore will usually be found to be in particles so small as to be fusible, it will sometimes be the case that nuggets of considerable size will constitute the circuit completing elements. In such case, these nuggets may not be fused, and it will become desirable to remove them by hand. In order to apprise the operator when this condition exists, I may include, in the electric circuit, an electric signal, such as a bell *Z*. While this bell will sound at any time that the circuit is completed, it will usually ring only momentarily, or until the metallic particle is fused. When a nugget of considerable size completes the circuit, the operator will be apprised of that fact by the ringing of the bell through a much longer period, and he will then seek and remove the nugget.

Having described my invention, what I claim is:

1. Separating apparatus of the character described, comprising a pair of spaced electrodes, an electric circuit in which said electrodes are included, and means for feeding material of varying degrees of conductivity over said electrodes, the said electric circuit being completed by the deposit of conductive material between the electrodes from said material, and electrically actuated means included in said circuit for breaking the circuit at another point, upon its completion at the electrodes.

2. A device of the character described, comprising a pair of spaced electrodes, one of which travels, an electric circuit in which said electrodes are included and means for feeding material of varying degrees of conductivity over said electrodes, the said electric circuit being completed by the deposit of a conductive content of said material between the electrodes, and an electrically controlled circuit breaker in said circuit for interrupting the same upon the completion of said circuit, at the electrodes.

3. Apparatus of the character described, comprising a pair of elongated electrodes having parallel confronting surfaces, an electric circuit in which said electrodes are included, and means for supporting said electrodes at an angle to the horizontal to cause material of varying degrees of conductivity fed to said electrodes to travel longitudinally over said elongated electrodes, the electric circuit being completed by the deposit of a conductive content of said material between the confronting surfaces of said electrodes.

4. Apparatus of the character described, comprising a pair of elongated electrodes having parallel confronting surfaces, an electric circuit in which said electrodes are included, and means for feeding material of varying degrees of conductivity longitudinally over said elongated electrodes, the electric circuit being completed by the deposit of a conductive content of said material between

the confronting surfaces of said electrodes, and an electrically controlled circuit breaker in series in said circuit and acting to interrupt the same upon the completion of the circuit at the electrodes.

5. A device of the character described, comprising a pair of longitudinally extending elongated electrodes having parallel confronting faces, one of said electrodes being in the form of a circular roll, means for rotating said roll, an electric circuit in which said electrodes are included, said circuit being completed by the deposit of conductive material, between the confronting surfaces of said electrodes, and means for causing metal bearing ores to travel in one direction lengthwise over said electrodes.

10. A device of the character described, comprising a pair of longitudinally extending elongated electrodes having parallel confronting faces, one of said electrodes being in the form of a circular roll, means for rotating said roll, an electric circuit in which said electrodes are included, said circuit being completed by the deposit of conductive material, between the confronting surfaces of said electrodes, and means for causing metal bearing ores to travel in one direction lengthwise over said electrodes.

15. A device of the character described, comprising a pair of longitudinally extending elongated electrodes having parallel confronting faces, one of said electrodes being in the form of a circular roll, means for rotating said roll, an electric circuit in which said electrodes are included, said circuit being completed by the deposit of conductive material, between the confronting surfaces of said electrodes, and means for causing metal bearing ores to travel in one direction over said electrodes, and means for removing fused 25 metals from said roll.

20. A device of the character described, comprising a pair of longitudinally extending electrodes having parallel confronting surfaces, one of which travels without changing its 30 distance from the other, an electric circuit in which said electrodes are included, and means for feeding material of varying degrees of conductivity longitudinally over said longitudinally extending electrodes, the electric 35 circuit being completed by the deposit of a conductive content of said material, and means for removing fused metals from said travelling electrode.

25. A separating apparatus of the character described, comprising an elongated plate of inverted V-shape, constituting one of the electrodes of an electric circuit, and a pair of longitudinally extending rollers mounted for rotation upon opposite sides of said plate 40 and in close proximity thereto, said rollers constituting the other electrode of said circuit, means for rotating said rollers, and an electric circuit in which said electrodes are included, said electric circuit being completed 45 by the deposit of material between them.

30. A separating apparatus of the character described, comprising an elongated plate of inverted V-shape, constituting one of the electrodes of an electric circuit, and a pair of longitudinally extending rollers mounted for rotation upon opposite sides of said plate and in close proximity thereto, said rollers constituting the other electrode of said circuit, 35 means for rotating said rollers, an electric circuit in which said electrodes are included,

said electric circuit being completed by the deposit of material between them, and an electric circuit breaker in series in said circuit and acting to break the circuit after its completion at the electrodes, and until the movement of the roller carries the fused material 70 away from the plate.

35. A device of the character described, comprising a plate of inverted V-shape constituting a fixed electrode, and a pair of rollers, one upon each side of said plate and mounted for rotation in close proximity thereto but lying in parallelism therewith, means for supporting the plate and rollers at an incline so that ore fed upon said rollers will be caused to travel longitudinally therewith while being continuously agitated by the rotation of the rollers, an electric circuit in which the rollers, upon the one hand, and fixed plate upon the other hand, constitute spaced electrodes, the said circuit being completed by the deposit of a conductive content of said material between them.

40. A device of the character described, comprising a plate of inverted V-shape constituting a fixed electrode, and a pair of rollers, one upon each side of said plate and mounted for rotation in close proximity thereto but lying in parallelism therewith, means for supporting the plate and rollers at an incline so that ore fed upon said rollers will be caused to travel longitudinally therewith while being continuously agitated by the rotation of the rollers, an electric circuit in which the rollers, upon the one hand, and fixed plate upon the other hand, constitute spaced electrodes, the said circuit being completed by the deposit of a conductive content of said material between them, and an electric circuit breaker included in said circuit and operative by the completion of the circuit at the electrodes to break the circuit at another point until the movement of the rollers carries the fused metal particles away from the gap between the said electrodes.

45. A device of the character described, comprising a plate of inverted V-shape constituting a fixed electrode, and a pair of rollers, one upon each side of said plate and mounted for rotation in close proximity thereto but lying in parallelism therewith, means for supporting the plate and rollers at an incline so that ore fed upon said rollers will be caused to travel longitudinally therewith while being continuously agitated by the rotation of the rollers, an electric circuit in which the rollers, upon the one hand, and fixed plate upon the other hand, constitute spaced electrodes, the said circuit being completed by the deposit of a conductive content of said material between them, and means for varying the strength of the current in said circuit.

50. A separating apparatus of the character described, comprising a pair of elongated electrodes

- having parallel confronting surfaces, an electric circuit in which said electrodes are included, means for supporting said electrodes at an angle to the horizontal to cause material of varying degrees of conductivity fed
5 to said electrodes to travel longitudinally over said elongated electrodes, the electric circuit being completed by the deposit of a conductive content of said material between the confronting surfaces of said electrodes,
10 and means for varying the strength of the current in said circuit to accommodate materials of varying degrees of conductivity or fusibility.
14. Apparatus of the character described, comprising longitudinally extending electrodes having parallel confronting surfaces, one of which travels without changing its distance from the other, an electric circuit in
15 which said electrodes are included, and means for feeding material of varying degrees of conductivity longitudinally over said longitudinally extending electrodes, the electric circuit being completed by the deposit of a
20 conductive content of said material, and a circuit controlling and regulating device included in series in said circuit, comprising a solenoid magnet, a movable contact point and a fixed contact point, the latter contact points
25 being included in the circuit so that when the solenoid is energized said contact points will be separated to interrupt the circuit.
15. Separating apparatus of the character described, comprising a pair of spaced electrodes, an electric circuit in which said electrodes are included, and means for feeding material of varying degrees of conductivity over said electrodes, and an electric signalling means included in said circuit.
40 In testimony whereof he affixes his signature.

RALPH SHERER.
